UNITED STATES PATENT OFFICE.

CHARLES THOMAS MASON, OF SUMTER, SOUTH CAROLINA, ASSIGNOR TO SPLITDORF ELECTRICAL COMPANY, OF NEWARK, NEW JERSEY, A CORPORATION OF NEW JERSEY.

DESIGN FOR A DISTRIBUTER-BLOCK FOR IGNITION DEVICES.

51,442.

Specification for Design.

Patented Oct. 30, 1917.

Original application filed May 10, 1915, Serial No. 27,277. Divided and this application filed May 15, 1916. Serial No. 97,746. Term of patent 14 years.

To all whom it may concern:

Be it known that I, CHARLES THOMAS MASON, a citizen of the United States, residing at Sumter, in the county of Sumter and State of South Carolina, have invented a new and original and ornamental Design for Distributer-Blocks for Ignition Devices, of which the following is a specification, reference being had to the accompanying drawing.

The subject matter of this new design is

divided out from my application Serial Number 27277 filed May 10th, 1915 and in the accompanying drawing Figure 1 is an end elevation of the distributer block and Fig. 2 a side elevation thereof.

I claim:

The ornamental design for a distributer block for ignition devices as shown.

CHARLES THOMAS MASON.
